Primary Examiner — Leanne Was-Englehart(57) **CLAIM**

The ornamental design for a pet door assembly, as shown and described.

DESCRIPTION

FIG. 1 is a front view of a pet door assembly showing my new design;

FIG. 2 is a rear view of the pet door assembly;

FIG. 3 is a right side view of the pet door assembly;

FIG. 4 is a left side view of the pet door assembly;

FIG. 5 is a top view of the pet door assembly;

FIG. 6 is a bottom view of the pet door assembly;

FIG. 7 is a top front side perspective view of the pet door assembly; and,

FIG. 8 is a top front side perspective view of the pet door assembly in use.

The broken lines in FIG. 2 depict portions of the pet door assembly that form no part of the claimed design. The broken lines in FIG. 8 illustrate environmental structure forming no part of the claimed design.

1 Claim, 6 Drawing Sheets(56)
